US0D1102458S

(12) **United States Design Patent** (10) **Patent No.:** **US D1,102,458 S**
(45) **Date of Patent:** **** Nov. 18, 2025**

(54) **DISPLAY SCREEN WITH GRAPHICAL USER INTERFACE**

(71) Applicant: **Airbnb, Inc.**, San Francisco, CA (US)

(72) Inventors: **Min Liu**, San Francisco, CA (US);
Elizabeth Lin, San Francisco, CA (US);
Teofila Connor, San Francisco, CA
(US); **David Muro**, San Francisco, CA
(US)

(73) Assignee: **Airbnb, Inc.**, San Francisco, CA (US)

(**) Term: **15 Years**

(21) Appl. No.: **29/950,524**

(22) Filed: **Jul. 3, 2024**

Related U.S. Application Data

(63) Continuation of application No. 29/838,032, filed on May 10, 2022, now Pat. No. Des. 1,039,543.

CLAIM

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.

1 Claim, 1 Drawing Sheet
